INVENTOR,

UNITED STATES PATENT OFFICE.

WILLIAM LEWIS EVANS, JR., OF WASHINGTON, INDIANA.

HINGE.

1,407,740.

Specification of Letters Patent. Patented Feb. 28, 1922.

Application filed February 24, 1921. Serial No. 447,418.

To all whom it may concern:

Be it known that I, WILLIAM L. EVANS, Jr., a citizen of the United States, residing at Washington, in the county of Daviess and State of Indiana, have invented a new and useful Hinge, of which the following is a specification.

This invention relates to hinges of the multiple pivot type, in which a jamb plate and a door plate are combined with a pair of arms, the opposite ends of which are pivoted respectively to the ends of said plates in such relation to each other that they always assume a non-parallel position.

The invention is generally an improvement upon the hinge shown, described and claimed in my Patent No. 1,367,954, dated February 8, 1921, but is more specifically an improvement on the construction of hinge shown, described and claimed in my co-pending application, Serial No. 346,455, filed Dec. 22, 1919. In said application, I have shown the jamb plate made angular in form having at opposite ends vertical holes or sockets which, when the jamb plate is applied to the door jamb, disposes said holes or sockets respectively inside and outside the entrance or opening closed by the door, and in different vertical planes. Associated with the angular jamb plate is a door plate rigidly mounted on the door, and also having a pair of holes or sockets. Fitted in the holes or sockets in the jamb plate and door plate, respectively, are the downturned and upturned ends of a pair of swinging arms, said arms being removable from the jamb plate and door plate at will.

The hinge disclosed in said application is designed to be used on toilet or partition doors which are shorter in height than the adjoining jamb to which the door is hung, the jamb extending both above and below the door a sufficient distance to receive the jamb plate. Such a construction could not be used where the door and jamb are of equal length and come even or flush with each other at the top and bottom, for there would then be nothing to which to fasten the jamb plate.

To construct a hinge which may be used in connection with toilet or partition doors, where the door and jamb are substantially the same height from the floor, is the special object of this invention.

To carry out this object, the arms of the

hinge have their ends bent parallel to each other and in the same direction and at right angles to the horizontal portion of the arms, and to secure the arms in the sockets to prevent them from dropping out, said arms are provided with means for retaining the same in place.

A further improvement is the construction of the jamb hinge member formed in two pieces located on each side of the jamb and connected together by a bolt.

The invention will be best understood from a consideration of the following detailed description, taken in connection with the accompanying drawings forming part of this specification, with the further understanding that while the drawings show a practical form of the invention, the latter is not confined to strict conformity with the showing of the drawings, but may be changed and modified so long as such changes and modifications come within the scope of the appended claims.

Referring to the drawings:—

Fig. 1 is a front elevation representing the upper and lower hinges and sections of a door, the intermediate portion of the door and jamb being broken away in order to show the construction of the hinges more clearly.

Fig. 2 is a top plan view of the upper hinge shown applied to the door and jamb and illustrating the parts on an enlarged scale, showing in full lines the closed position of the door, and in dotted lines an intermediate and the open position.

Fig. 3 is a vertical section on the line 3—3, Fig. 1.

Fig. 4 is a front elevation of a toilet partition on a reduced scale showing the improved hinge applied to the door thereof.

Like reference characters indicate corresponding parts in the several figures of the drawing.

As hereinbefore stated, the hinge of the present invention is especially useful for toilet or partition doors where the door jamb is of substantially the same length as the door, causing the top and bottom of the door and jamb to be in line or flush with each other. The hinge of the present invention differs in several important respects from the hinge of the aforesaid application, and they will now be specifically referred to.

Each hinge is identical, and since they are

duplicates of each other, a description of the upper hinge will suffice for the full disclosure of the invention.

The arms 10 and 11, which are of the same length, have downturned terminals 10^a and 11^a, respectively, which are bent at exactly right angles to the horizontal portions of the arms, and extend in the same direction and are parallel to each other. The arm 10, 10 which is the outer arm, being located on the outside of the door when closed, is set higher than the lower arm 11, in order that they may not clash with each other during their swinging movement, the arms operating 15 in different horizontal planes.

Instead of making the jamb hinge member angular in form, as in the aforesaid application, it is constructed of two plates 12 and 12^a, respectively, each having a pair of 20 downturned vertically alined eyes 13 and 13^a, respectively, which are separated from each other at about the horizontal center of the jamb member, for a purpose which will be presently described. These eyes form openings or sockets to receive the downturned 25 ends 10^a and 11^a. One of the plates is arranged on the inside of the jamb, and the other on the outside, both in the same horizontal plane, and they are connected by bolts 30 and nuts 14 and 15, respectively, thereby making a secure fastening, and one which is not likely to split off the jamb. As previously stated, the ends 10^a and 11^a of the arms 10 and 11 enter the alined eyes 13 and 35 13^a of the jamb plates 12 and 12^a. In order to retain them in place, a collar 16 is mounted on said ends and held rigidly thereon by a pin or rivet 17, or any equivalent means. This fastens the collar 16 in place, and permits 40 it to revolve with the arms between the eyes 13 and 13^a.

Door plate or member 18 has eyes 19 and 19^a in pairs at each end thereof, said eyes being constructed similar to the eyes 13 and 45 13^a of the jamb plates, being vertically alined and spaced from each other at the horizontal center of the plate, at which place a collar 20 is mounted on each of the ends 10^a and 11^a of the arms 10 and 11, and each collar is 50 secured by a pin 21, being precisely the same construction as in the case of the jamb plates. The collars 20 of the door plate revolve with the arms 10 and 11 between the eyes 19 and 19^a, and sustain the weight of the door. 55 By this arrangement, part of the weight and strain is placed upon the upper hinge, as will be obvious.

The application of the hinge to a toilet or partition door where the door jamb and door 60 extend above the floor the same height, is shown in Fig. 4, but it is obvious, that while this hinge is specially adapted for this purpose, it will work just as well with the jamb above or below the door, or the same length 65 as the door.

When applied as shown in the drawings, with the door jamb and door having the same length and being substantially flush with each other at the top and bottom edges, the jamb plates and the door plates are arranged in the same horizontal line, but the arms swing in different horizontal planes, in this respect presenting a marked difference over the construction shown in my aforesaid application.

The movement of the door in swinging from an open to a closed position, is shown in Fig. 2 of the drawings, it being noted that because the arms are arranged in different horizontal planes they are caused to 70 swing across the door jamb and door, without, however, clashing with each other or with the parts referred to. In no position of the movement of the arms are they in exact parallel relation.

What is claimed is:—

1. The combination with a door and door jamb, of a member secured to the jamb and having eyes or sockets, a plate secured to the door and also having eyes or sockets, 90 said jamb member and said door plate being disposed in the same horizontal plane, and a pair of arms spaced apart and having their ends bent and extending in the same direction, and pivotally mounted in the eyes 95 or sockets of the jamb member and door plate.

2. The combination with a door and a door jamb, of means for pivotally connecting the door to the door jamb, comprising a jamb 100 member having a pair of eyes or sockets disposed on opposite sides of the jamb, a door plate having a pair of eyes or sockets disposed on the same side of the door, and a pair of arms having their ends bent in the 105 same direction and mounted, respectively, in the eyes of the jamb member and door plate.

3. The combination with a door and a door jamb, of means for pivotally connecting the door to the jamb, comprising a jamb member 110 having eyes arranged on opposite sides of the jamb, a door plate secured to the face of the door and having a pair of spaced eyes arranged on the same side of the door, and a pair of swinging arms having their ends bent in the same direction and mounted in the eyes of the jamb member and door plate, respectively, said arms being mounted to swing in different horizontal planes, with the straight portions of 115 the arms arranged below the lower edge of the door.

4. The combination with a door and a door jamb, of means for pivotally connecting the door to the jamb, comprising a jamb 125 member having sockets arranged on opposite faces of the jamb but in the same horizontal plane and at an angle to each other, a door plate fastened to the door and having sockets arranged on the same side of 130

the door, and a pair of arms having outturned ends arranged in the same vertical plane and substantially parallel with each other, said arms being fitted in the sockets 5 of the door plate and jamb member, respectively, thereby disposing said arms at an angle to each other, with one arm crossing the door and the other arm substantially parallel with the door when the latter is in 10 its closed position.

5. The combination with a door jamb and a door, of means for pivotally connecting the door to the door jamb, comprising a 15 pair of arms of substantially equal length having outturned ends extending in the same direction at right angles to the main portion of the arms and substantially parallel to each other, a jamb member secured to the jamb having sockets arranged on opposite 20 faces of the jamb but in the same horizontal plane, and a door plate secured to the door and having its sockets disposed on the same side of the door, said sockets of the door plate and jamb member being adapted to 25 receive the outturned ends of said arms, and means for holding the said outturned ends of the arms in said sockets.

6. The combination with a door jamb and a door, of means for pivotally connecting 30 the door to the door jamb, comprising a pair of arms of substantially equal length having outturned ends arranged at substantially right angles to the main portion of the arms and substantially parallel to each 35 other, a jamb member secured to the jamb and having hinge eyes located on opposite sides of the jamb, a door plate secured to the door and having hinge eyes located on the same side of the door, said eyes of the 40 jamb member and door plate being adapted to receive the outturned ends of the arms, and means mounted on the ends of said arms and carried thereby to hold the arms in the eyes of said members.

45 7. The combination with a door jamb and a door, of means for pivotally connecting the door to the door jamb, comprising a pair of arms having outturned ends extending in the same direction, a jamb member secured 50 to the jamb and comprising a pair of plates secured on opposite sides of the jamb but in the same horizontal plane, each plate having a pair of spaced alined eyes, a door plate secured to the door and having two 55 pairs of eyes arranged in vertical alinement and spaced from each other, the outturned ends of the arms fitting in the alined eyes of the jamb member and door plate, respectively, and a collar mounted on each of the

outturned ends of said arms and in the 60 spaces between the eyes and sustaining the weight of the door.

8. The combination with a door jamb and a door, of means for pivotally connecting the door to the door jamb, comprising a 65 jamb member secured to opposite faces of the jamb and a door plate secured to the door, both in the same horizontal plane, and a pair of swinging arms spaced from each other and pivotally mounted in the jamb 70 member and door plate, respectively, and operating in different horizontal planes, thereby disposing said arms at an angle to each other, with one arm crossing the other.

9. The combination with a door jamb and a door, of means for pivotally connecting the door to the jamb, comprising an upper hinge and a lower hinge, each hinge consisting of a pair of swinging arms, with each arm operating in different horizontal 80 planes, a door plate secured to the door, and a jamb member secured to the jamb, both in the same horizontal plane at the top and bottom, respectively, said jamb member and door plate having eyes, and the 85 arms of the upper hinge having downturned ends and the arms of the lower hinge having upturned ends, the ends of said arms turning in the eyes of said plate and jamb member, respectively, and means for holding 90 the ends of said arms in said eyes, whereby part of the weight and strain of the door is placed upon the upper hinge.

10. A hinge for use in connection with toilet or partition doors, where the door 95 and door jamb are substantially flush with each other at the top and bottom of the door, comprising an upper and a lower hinge, each hinge comprising a pair of arms having outturned ends extending in the same 100 direction, a door plate secured to the door and having eyes to receive one of the ends of each of the arms, and a jamb member secured to the jamb and having eyes to receive the other of the ends of said arms, said 105 jamb member and door plate being arranged in substantially the same horizontal plane, and substantially flush with the upper and lower edges of the door and jamb, respectively, and means for holding the outturned 110 ends of the arms in said eyes, whereby part of the weight and strain of the door is placed upon the upper hinge.

In testimony that I claim the foregoing as my own, I have hereto affixed my signature.

WILLIAM LEWIS EVANS, JR.
